NO. 53.

H. A. NORRIS.
BORING, TAPPING, &c.

No. 53.

Reissued Sept. 9, 1843.

UNITED STATES PATENT OFFICE.

H. A. NORRIS, OF NEW YORK, N. Y.

MACHINE FOR BORING, TAPPING, AND REAMING WATER-PIPES UNDER HYDROSTATIC PRESSURE.

Specification forming part of Letters Patent No. 2,794, dated September 30, 1842; Reissued September 9, 1843, No. 53.

To all whom it may concern:

Be it known that I, H. ARIEL NORRIS, of the city, county, and State of New York, have invented a new and useful machine for 5 boring, tapping, and reaming water or other pipes under hydrostatic pressure and for making thereto connections of lateral or service pipes; and I hereby declare the following to be a full and accurate description 10 thereof, reference being had to the annexed drawings, making part of this specification and representing the machine attached to a pipe ready for operation.

To bore the pipe P, the base B of the machine is laid upon the pipe and strongly pressed upon it by the chain or band J passing around the pipe and drawn tight by screws working through the cross-bar C. A mandrel M, attached to the base B supports 20 a swinging frame A E, in a collar of which the drill S works; and to another part D of the frame the ferule F (or connecting tube to which the lateral pipe is to be attached) is fixed. A downward pressure is given to the 25 drill by the lever L working against a shoulder upon its shaft. By turning the crank K, the hole is bored; when the escape of water will be but slight. For before the thickness of the metal is drilled, the reamer or tap as 30 the case may be, will have entered the orifice thereby nearly closing it. The opening being thus drilled, and tapped or reamed, is now ready for the insertion of the ferule. Raising the lever, and with it the drill and 35 shaft, the movable part of the machine is rapidly swung so as to bring the ferule immediately over the opening into which it may be at once screwed by turning the shaft S' working in the frame A E, or, if it is preferred to drive it instead of screwing it, this 40 may be done either by driving the shaft S' or by a lever working similarly to the lever L. Thus the water is allowed to escape for only the short time requisite to raise the lever L and carry it over a short space. A pin 45 N is fixed in the mandrel so as to arrest the motion of the frame when the ferule is accurately over the orifice. The principal effect of this machine could be produced by 50 letting the end of the frame slide lengthwise in guides attached to the base B, instead of revolving upon the mandrel as described. Or, the drill and ferule may move each upon a separate frame, instead of being connected by the same one; and, though less 55 convenient, would have a similar effect. Or

the drill may work in a moving frame and the ferule shaft in a stationary one, directly above it; the drill being removed upon the completion of the orifice, the ferule-shaft 60 may be made to slide rapidly down to the orifice and the ferule thus inserted; or vice versa, the drill may occupy the stationary frame and the ferule the moving one. In all these combinations the object desired is 65 to remove the drill from the orifice and bring the ferule instantly into its place; thus avoiding the inconvenience that would result from a flow of water, in the interim, were the operation less promptly performed. 70

I claim as my invention and desire to secure by Letters Patent:

1. The connection of the ferule and drill-shaft with each other by means of a sliding or swinging frame upon which both of them 75 work according to the principles herein set forth, and by which either is removed and the other instantly brought to its place; thus avoiding the necessity of a valve to prevent the flow of water in the interim.

2. I also claim the ferule-shaft (or any analogous device substantially as herein described for holding the ferule for insertion) working in a sliding or swinging frame as 80 herein described, in combination with the drill whether working in the same frame or not.

3. And I further claim the drill working in a sliding or swinging frame as herein described, in combination with the ferule-shaft whether working in the same frame or 85 not.

4. And I further claim the combination or successive application (without the intervention of a valve) of the drill and ferule-shaft or holder, whereby both the valve and the close chamber of my patent of August 11, 1842, are dispensed with. 90

The term "frame" herein used is intended to signify the body or structure used to support the drill in its place while in action or to remove it when its work is done—likewise the structure or body by which the ferule-shaft or ferule holder is guided with exactness to the orifice and the insertion secured notwithstanding the pressure of the water. 100

H. ARIEL NORRIS.
